TWO-STAGE CONTINUOUS CARBONIZATION
ACTIVATION PROCESSKenneth B. Stuart, Denver, Colo., assignor to The
Colorado Fuel & Iron Corporation, a corpora-
tion of Colorado

Application March 4, 1948, Serial No. 12,963

11 Claims. (Cl. 252—421)

1

This invention relates to method of producing activated carbon and has for its object certain improvements in such method for producing activated carbon of uniform high quality.

In the production of activated carbon, it is customary first to char or carbonize suitable raw carbonaceous material and then to activate it, usually with a hot mildly oxidizing gas, such as superheated steam. To this end, the activating gas is passed into a column of previously charred carbonaceous material. The gas tends to channel its way through the column of char, following the line of least resistance, with the result that the char is not uniformly activated.

Investigations confirm my discovery that a method may be employed in which the carbonaceous material may be successively carbonized and activated, the steps of the method being so arranged as to assure substantially uniform distribution of the carbonizing and activating gases among the solid particles of carbonaceous material. In this way each carbon particle receives substantially the same treatment.

The apparatus employed comprises an upright retort with an inlet at the top for ingress of carbonaceous material and an outlet at the bottom for egress of activated carbon, the retort being divided into an upper carbonizing chamber and a lower activating chamber with a partition disposed between the two chambers with at least one opening therein for the passage downwardly of char from the upper chamber to the lower chamber and for the passage upwardly of gases from the lower chamber to the upper chamber. An automatic pressure controlled valve outlet extends through the wall of the retort and connects the upper portion of the upper chamber for the passage of exhaust gases from the retort.

A manifold is advantageously disposed in the upper portion of the lower chamber, an inlet extending through the wall of the retort and connecting the manifold for the passage of activating gas into the manifold. A plurality of spaced and perforated down-pipes depend from the manifold deeply into the lower chamber for the passage of activating gas from the manifold to the lower chamber. Another manifold is disposed in the upper portion of the upper chamber, with one or more conduits connecting the upper portion of the lower chamber with the latter manifold. A plurality of spaced and perforated down-pipes depend from the latter manifold deeply into the upper chamber for the passage of carbonizing gases from the latter manifold into the upper chamber.

2

The partition between the two chambers is also advantageously in the form of a hopper depending into the lower chamber to provide an open space in the upper portion above the normal level of carbon confined in the lower chamber to reduce the velocity of gases sweeping through the retort, thereby permitting the dropping of suspended fines. The upper portion of the lower chamber is preferably substantially greater in cross-sectional area than the main portion of the chamber to provide an enlarged space. This space may be regarded as a detention zone in which the velocity of the gas is reduced to drop the suspended fines while at the same time keeping the hot gas in the detention zone in direct contact and heat interchange relationship with the carbon to help provide the heat necessary to effect the desired activation.

The inlet at the top of the retort is preferably in the form of a conduit depending into the upper chamber to provide an open space above the normal level of carbon confined in the upper chamber to reduce the velocity of gases rising upwardly through the retort and thereby permitting the dropping of suspended fines. As with the lower chamber, the upper portion of the upper chamber is preferably substantially greater in cross-sectional area than the main portion of the chamber to provide additional space. This space also functions as a detention zone in which the velocity of the gases is reduced and suspended fines carried by the gases are dropped as they sweep through the carbonizing zone. While in the detention zone, the still hot gases are in direct contact and hence in heat interchange relationship with the carbon to help provide the heat necessary to effect the desired carbonization.

So that the carbonizing and activating steps may be conducted under pressure, the inlet at the top of the retort communicates with a charge chamber, a valve being disposed between the charge chamber and the inlet to open and close the passageway between the two. With an arrangement such as this, the valve may be opened to permit the passage of a charge of the raw carbonaceous material into the retort, after which the valve may be closed to prevent the escape of exhaust gases by way of the charge chamber. Exhaust gases are bled from the retort through the automatic pressure controlled valve outlet leading from the upper chamber.

The outlet at the bottom of the retort communicates with a cooling chamber, a valve being disposed between the outlet and the cooling

chamber to open and close the passageway between the two. A star discharge is preferably located at the outlet to transfer activated carbon from the retort to the cooling chamber. With the valve closed, pressure conditions may be maintained within the retort. From time to time the valve may be opened and the star discharge operated to transfer activated carbon from the retort to the cooling chamber, after which the valve is again closed to restore the desired pressure conditions within the retort.

In accordance with the method of the invention, a continuous body of finely divided carbonaceous material is advanced through a carbonizing zone, a constricted passageway and an activating zone, the particles of char moving relatively to one another as they pass through the constricted passageway to effect their mixing. Hot activating gas under substantial positive pressure is passed through the char in the activating zone. Hot gases from the activating zone while still under substantial positive pressure are passed through the carbonaceous material in the carbonizing zone and into a gas detention zone directly above its normal level in the zone. The velocity of the gases is reduced as they enter the detention zone to drop suspended carbon fines carried by the gases as they sweep through the body of carbon. While in the detention zone the gases are kept in direct contact and hence in heat-interchange relationship with the carbon to help provide the heat necessary to effect the desired carbonization. And the exhaust gases are withdrawn from the detention zone while maintaining all of the zones under substantial positive pressure.

In a presently preferred practice, hot gases from the activating zone are passed into a gas detention zone directly above the normal level of the char in the activating zone. The velocity of the gases is reduced as they enter the latter detention zone to drop suspended fines carried by the gases as they sweep through the activating zone. While in the latter detention zone, the hot gases are kept in direct contact and hence in heat-interchange relationship with the carbon to help provide the heat necessary to effect the desired activation.

Also, the hot activating gas is preferably released in a plurality of small streams at a plurality of points distributed throughout the char in the activating zone to get a substantially even distribution of the gas. It is preferred similarly to release hot gases from the activating zone in a plurality of streams at a plurality of points distributed throughout the char in the carbonizing zone.

These and other features of the invention will be better understood by referring to the accompanying drawing, taken in conjunction with the following description, which diagrammatically shows an apparatus that may be employed in a practice of the invention.

The apparatus shown comprises a retort 10 having a heavy outer insulating jacket 11. The retort stands in an upright or vertical position and is generally cylindrical in plan, being divided into an upper or carbonizing chamber 12 and a lower or activating chamber 13. The two chambers are separated by a partition in the form of a hopper 14 with a depending outlet 15 to provide an open space in the upper portion of the lower chamber above the normal level of carbon confined in that chamber. The upper portion of the lower chamber is in the form of a bulged-

out or enlarged section 18, making it substantially greater in cross-sectional area than the main portion of the chamber, to provide additional open space in the upper portion of the lower chamber. The lower portion of the lower chamber is in the form of an inverted frustoconical section or hopper 19, with a depending outlet 20. The top of the retort is fitted with a depending inlet 22 to provide an open space in the upper portion of the upper chamber. The upper portion of the upper chamber is in the form of a bulged-out or enlarged section 23, making it substantially greater in cross-sectional area than the main portion of the chamber, to provide additional open space in the upper portion of the upper chamber.

A manifold 25, generally annular in shape, is disposed horizontally directly below the side wall of the hopper 14 and around depending outlet 20 in the open space in the upper portion of lower chamber 13. An inlet 26 extends through the wall of the retort and connects the manifold for the passage of activating gas into the manifold. A plurality of spaced and perforated down-pipes 27 depend from the manifold deeply into the lower chamber for the passage of activating gas from the manifold to the lower chamber. The number of down-pipes and perforations is such as to assure a substantially even distribution of the activating gas in the body of char undergoing activation in the lower chamber.

A second manifold 30, also generally annular in shape, is disposed horizontally directly below the top wall of the retort and around depending inlet 22 in the open space in the upper portion of upper chamber 12. As shown, the manifold is supported on the side wall of hopper 14 by means of three vertical pipes 31 spaced at 120° angles. A plurality of spaced and perforated down-pipes 32 depend from the manifold deeply into the upper chamber for the passage of gases into the upper chamber from the manifold. The number of down-pipes and their perforations is such as to assure a substantially even dispersion of exhaust gases to the carbon undergoing charring in the upper chamber. A valved outlet 33 extends through the wall of the retort for the controlled passage of exhaust gases from the retort.

Inlet 22 at the top of the retort connects with a charge chamber 35 and a measuring bin 36, a valve 37 being interposed between the measuring bin and the charge chamber. A similar valve 38 is disposed between the charge chamber and the inlet of the retort.

Outlet 20 at the bottom of the retort connects with a charge chamber 40 fitted with an openable closure 41. In the specific construction shown, a star discharge 42 is associated with the outlet of the retort to facilitate removal of activated carbon therefrom. A valve 43 is interposed between the star discharge and the charge chamber.

The apparatus may be operated as follows: Suitable carbonaceous material, such as finely divided anthracite coal, is fed into retort 10 until lower activating chamber 13 and upper carbonizing chamber 12 are filled. To this end, valve 43 is closed and valves 38 and 37 are opened, carbon being passed successively through measuring bin 36, and charge chamber 35, into the retort. When the lower and upper chambers are filled, valve 38 is closed.

Suitable activating gas is passed under positive pressure through valved inlet 26 into mani-

fold 25 and then through perforated down-pipes 21 into the body of char confined in lower chamber 13. Due to the substantially even distribution of the relatively large number of perforated down-pipes, the activating gas is released substantially evenly throughout the body of char. The hot gas rises upwardly in the lower chamber in sweeping contact with the particles of char until it reaches the space in bulged-out section 18 above the top level of the body of char. This space may be considered a gas detention zone directly above the normal level of the char in the activating zone. The velocity of the gas is reduced as it enters the detention zone and drops suspended fines carried by the gas as it sweeps upwardly through the activating zone. While the hot gas is in the detention zone it remains in direct contact, and hence in heat-interchange relationship, with the carbon to help provide the heat necessary to effect the desired activation.

The hot gases then pass from the detention and activating zones, while still under substantial positive pressure, through pipes 31 into upper manifold 38 and then enter perforated down-pipes 32. Due to the substantially even distribution of the relatively large number of perforated down-pipes, the spent activating gases are distributed substantially evenly throughout the body of char. The gases rise completely through the body of char and enter bulged-out section 23 to the space above the normal level of the body of char confined in the upper chamber. This space may also be regarded as a detention zone, in which the velocity of the gases is reduced to permit the dropping of suspended fines carried by the gases. The still hot gases in the detention zone are kept in direct contact, and hence in heat interchange relationship, with the char to help provide the heat necessary to effect the desired carbonization. The spent or exhaust gases pass out of valved outlet 33 while still under substantial positive pressure.

Activation of carbon in the lower chamber and charring of carbon in the upper chamber take place simultaneously. When the char in the lower chamber, particularly the lower portion of the lower chamber, is suitably activated, discharge valve 43 is opened and star discharge 42 is operated to withdraw activated carbon from the lower chamber to cooling chamber 40. As this occurs, the char above in both the lower and upper chambers settles or moves downwardly, thus leaving space in the upper portion of the upper chamber for additional carbon. After a desired amount of activated carbon is withdrawn, rotation of the star discharge is terminated and the discharge valve is closed; and after the activated carbon is cooled, closure 41 is opened to remove the carbon.

Additional carbonaceous material is placed in measuring bin 36 and passed into charge chamber 35. Valve 37 is closed and valve 38 is opened to drop the material through inlet 22 into the lower chamber.

The discharging and charging operations are conducted intermittently. The material in the upper and lower chambers in effect forms a continuous column which is progressively advanced by gravity through the retort. Due to the controlled manner in which the activating gas is introduced and the spent gases are withdrawn, the activating and carbonizing steps may be conducted under suitable pressure conditions. As the particles of carbon move downwardly through bulged-out section 23, and rub against

down-pipes 32 and the side wall of the upper chamber and pass into restricted passageway 15 at the bottom of hopper 14, a gentle mixing action is obtained. This mixing action is continued as the charred carbon particles move through the restricted passageway and spread laterally across the retort, and as they move downwardly through bulged-out section 18 and rub against down-pipes 27 and the side wall of the lower chamber. The net effect is to combine gentle mixing with substantially even distribution of the heating gases, thus assuring substantially uniform treatment of the carbon particles.

Clogging of the manifolds and the down-pipes is prevented by keeping the gases substantially free of suspended fines. The gases tend to pick up fine solids in both the lower or activating chamber and the upper or carbonizing chamber and these solids would soon clog restricted openings if means were not provided to drop them out of the gas stream. These means comprise the bulged-out or expanded sections, the depending inlet and the hopper or funnel with its depending outlet between the two chambers. In these portions of the apparatus, the velocity of the gases is reduced to a point where the solids drop out. Another desirable feature of the apparatus is that the retort as a whole contains substantially no dead space in which to hold up movement of the material. The structure shown is such as to insure substantially uniform charring and activation of the carbon.

Activating gases of various kinds may be employed. The most common are steam and carbon dioxide, or both. Activating gas may be obtained, for example, by burning combustible gas under pressure in air. The activating step is conducted under positive pressure, that is, super-atmospheric pressure. This may vary over a rather wide range but should be substantial, preferably in excess of 5 pounds per square inch gauge pressure. I have had excellent results with pressures in the neighborhood of 20 pounds per square inch gauge pressure. The pressure must, however, be consistent with safety, depending upon the strength of the apparatus.

Similarly, carbonizing gases of various kinds may be employed. It is economical to use the gases from the activating step for the carbonizing step, as described. It is also preferable to conduct the carbonizing step under a substantial positive pressure, say of the same order as in the activating step.

The flow of activating and carbonizing gases through the lower and upper chambers should be substantial and may, of course, vary over a rather wide range. I have, for example, passed activating gas in contact with the char at a temperature of about 1400° F. to about 1600° F. and at a rate of about 100 to 240 standard cubic feet of gas per hour per 1 to 2 pounds of activated carbon produced from the char; and carbonizing gas in contact with the carbon (Colorado sub-bituminous coal) at the rate of about 2500 to 6000 standard cubic feet of gas per 25 to 50 pounds of char per hour. Activation and carbonization of the carbon may be effected in a number of ways, such for example as described in my copending application Serial No. 501,044, filed September 3, 1943, now U. S. 2,501,700.

It will be clear to those skilled in this art that the practice of the invention lends itself to a number of useful modifications.

I claim:

1. In the method of producing activated car-

bon, the improvement which comprises progressively advancing a continuous body of finely divided carbonaceous material through a carbonizing zone, a constricted passageway and an activating zone, the particles moving relatively to one another as they pass through the constricted passageway to effect their mixing, passing hot activating gas under substantial positive pressure through the char in the activating zone, passing hot gases from the activating zone while still under substantial positive pressure through the char in the carbonizing zone and into a gas detention zone directly above the normal level of the char in the carbonizing zone, reducing the velocity of the gases as they enter the detention zone to drop suspended carbon fines carried by the gases as they sweep through the body of char, keeping the gases while in the detention zone in direct contact and hence in heat-interchange relationship with the char to help provide the heat necessary to effect the desired carbonization, and withdrawing exhaust gases from the detention zone while maintaining all of the zones under substantial positive pressure.

2. Method according to claim 1, in which hot gases from the activating zone are passed into a gas detention zone directly above the normal level of the char in the activating zone, reducing the velocity of the gases as they enter the latter detention zone to drop suspended fines carried by the gases as they sweep through the activating zone, and keeping the hot gases while in the latter detention zone in direct contact and hence in heat-interchange relationship with the char to help provide the heat necessary to effect the desired activation.

3. Method according to claim 1, in which the hot activating gas is released in a plurality of small streams at a plurality of points distributed throughout the char in the activating zone to get a substantially even distribution of the gas, and in which hot gases from the activating zone are passed into a gas detention zone directly above the normal level of the char in the activating zone, reducing the velocity of the gases as they enter the latter detention zone to drop suspended fines carried by the gases as they sweep through the activating zone, and keeping the hot gases while in the latter detention zone in direct contact and hence in heat-interchange relationship with the char to help provide the heat necessary to effect the desired activation.

4. Method according to claim 1, in which the hot activating gas is released in a plurality of small streams at a plurality of points distributed throughout the char in the activating zone to get a substantially even distribution of the gas, and hot gases from the activating zone are released in a plurality of streams at a plurality of points distributed throughout the char in the carbonizing zone to get a substantially even distribution of the gases.

5. Method according to claim 1, in which a portion of the hot gases is passed from the activating zone through the relatively small body of char in the constricted passageway into the carbonizing zone, and another portion of the hot gases is withdrawn from the body of char in the activating zone at a plurality of points and passed into the carbonizing zone.

6. Method according to claim 1, in which a portion of the hot gases is passed from the activating zone through the relatively small body of

char in the constricted passageway into the carbonizing zone, and another portion of the hot gases is withdrawn from the body of char in the activating zone at a plurality of points and released at a plurality of points throughout the body of char in the carbonizing zone to get a substantially even distribution of the gases.

7. In the method of producing activated carbon, the improvement which comprises passing hot activating gas under substantial positive pressure through a body of finely divided char in an activating zone, passing hot gases from the activating zone while still under substantial pressure through a body of finely divided carbonaceous material in a carbonizing zone and into a gas detention zone directly above the normal level of the material in the carbonizing zone, reducing the velocity of the gases as they enter the detention zone to drop suspended carbon fines carried by the gases as they sweep through the body of material, keeping the gases while in the detention zone in direct contact and hence in heat-interchange relationship with the material to help provide the heat necessary to effect the desired carbonization, and withdrawing exhaust gases from the detention zone while maintaining all of the zones under substantial positive pressure.

8. Method according to claim 7, in which hot gases from the activating zone are passed into a gas detention zone directly above the normal level of the char in the activating zone, reducing the velocity of the gases as they enter the latter detention zone to drop suspended fines carried by the gases as they sweep through the activating zone, and keeping the hot gases while in the latter detention zone in direct contact and hence in heat-interchange relationship with the char to help provide the heat necessary to effect the desired activation.

9. Method according to claim 7, in which the hot activating gas is released in a plurality of small streams at a plurality of points distributed throughout the char in the activating zone to get a substantially even distribution of the gas, and hot gases from the activating zone are released in a plurality of streams at a plurality of points distributed throughout the body of material in the carbonizing zone to get a substantially even distribution of the gases.

10. In the method of producing activated carbon, the improvement which comprises progressively advancing a continuous body of finely divided carbonaceous material through a carbonizing zone, a constricted passageway and an activating zone, the particles moving relatively to one another as they pass through the constricted passageway to effect their mixing, passing hot activating gas under substantial positive pressure through the char in the activating zone and into a gas detention zone directly above the normal level of material in the carbonizing zone, reducing the velocity of the gases as they enter the detention zone to drop suspended carbon fines carried by the gases as they sweep through the body of material, keeping the gases while in the detention zone in direct contact and hence in heat-interchange relationship with the char to help provide the heat necessary to effect the desired activation, passing hot gases from the activating and detention zones while still under substantial positive pressure through the body of material in the carbonizing zone, and withdrawing exhaust gases from the carbonizing zone while maintaining all of the zones under substantial positive pressure.

11. In the method of producing activated carbon, the improvement which comprises passing hot activating gas under substantial positive pressure through a body of finely divided char in an activating zone, passing hot gases from the activating zone while still under substantial pressure through a body of finely divided carbonaceous material in a carbonizing zone and into a gas detention zone directly above the normal level of the material in the carbonizing zone, reducing the velocity of the gases as they enter the detention zone to drop suspended carbon fines carried by the gases as they sweep through the body of material, keeping the gases while in the detention zone in direct contact and hence in heat-interchange relationship with the material to help provide the heat necessary to effect the desired carbonization, and withdrawing exhaust gases from the detention zone while maintaining all of the zones under substantial positive pressure.

11. Method according to claim 10, in which the hot activating gas is released in a plurality of small streams at a plurality of points distributed throughout the char in the activating zone to get a substantially even distribution of the gas, and in which hot gases from the activating and detention zones are released in a plurality of streams at a plurality of points distributed through the body of material in the carbonizing zone to get a substantially even distribution of the gases.
